APPARATUS FOR THE CONTROL OF
RAILWAY CAR RETARDERS

John W. Livingston, Wilkinsburg, Pa., assignor to
The Union Switch & Signal Company, Swiss-
vale, Pa., a corporation of Pennsylvania

Original application February 11, 1932, Serial No.
592,262, now Patent No. 2,022,086. Divided and
this application May 3, 1935, Serial No. 19,711

6 Claims. (Cl. 303—20)

My invention relates to apparatus for the control of railway car retarders, and particularly to apparatus for controlling fluid pressure operated car retarders.

5 One object of my invention is to provide means for securing several different pressures in the actuating mechanism with a minimum number of line wires between the mechanism and its controller lever.

10 The present application is a division of my Patent No. 2,022,086, granted on Nov. 26, 1935, for Apparatus for the control of railway car retarders.

15 I will describe one form of apparatus embodying my invention, and will then point out the novel features thereof in claims.

The accompanying drawing is a diagrammatic view showing one form of apparatus embodying my invention.

20 Referring to the drawing, the reference character A¹ designates a car retarder comprising two braking bars 2 and 3, located on opposite sides of, and extending parallel with, one track rail 1 of a stretch B of railway track, and two similar braking bars 2^a and 3^a, located on opposite sides of, and extending parallel with, the other track rail 1^a of the stretch B.

25 The car retarder A¹ is controlled by a fluid pressure motor M¹ comprising a cylinder 4 containing a reciprocable piston 5 which is attached to a piston rod 5^a. The braking bars 2, 3, 2^a and 3^a are operatively connected with the piston rod 5^a of motor M¹ through a suitable linkage including a lever 6 pivoted at 6^a. When piston 5 of motor M¹ moves to its left-hand position, braking bars 3 and 3^a of car retarder A¹ are moved toward the right, and braking bars 2 and 2^a are moved toward the left, and the braking bars then occupy their ineffective or non-braking positions, as shown in the drawing. When piston 5 is moved to its right-hand position, however, the braking bars are each moved toward the associated rail to their effective or braking positions in which they engage the sides of the wheels of a railway vehicle traversing rails 1 and 1^a.

30 Motor M¹ is controlled by three magnet valves D¹, E¹ and F¹. These valves are similar and each comprises a valve stem 7, biased to an upper position by a spring 8 and provided with an armature 9 and a winding 10. When valve D¹ is energized, valve stem 7 of this valve moves downwardly against the bias exerted by spring 8, and a pipe 11 which communicates with the left-hand or application end of motor M¹, is then connected with a pipe 12 which is constantly sup-

plied with fluid pressure, usually air, from a suitable source not shown in the drawing. When valve D¹ is deenergized, however, valve stem 7 of this valve is moved upwardly by spring 8, and pipe 11 is then disconnected from pipe 12. When valve E¹ is energized, valve stem 7 of this valve moves downwardly, and pipe 11 is then connected with atmosphere through a pipe 13 and a port 14, but when valve E¹ is deenergized, pipe 11 is disconnected from atmosphere and a pipe 15 which communicates with the right-hand or restoring end of motor M¹, is vented to atmosphere through port 14. When valve F¹ is energized, valve stem 7 of this valve moves downwardly and connects pipe 15 with pipe 12, but when valve F¹ is deenergized, pipe 15 is disconnected from pipe 12. It will be apparent, therefore, that when valve D¹ is energized, the application end of motor M¹ is supplied with fluid pressure, and when valve F¹ is energized, the restoring end 10 of motor M¹ is supplied with fluid pressure. Furthermore, when valve E¹ is energized, the application end of motor M¹ is vented to atmosphere, and when valve E¹ is deenergized, the restoring end of motor M¹ is vented to atmosphere. 15

20 Valves D¹, E¹ and F¹ are controlled in part by a plurality of similar pressure responsive devices each designated by the reference character K with a distinguishing exponent and subscript. Referring to the pressure responsive device 30 K₁¹⁰⁻²⁰, for example, this device comprises a Bourdon tube 16, connected by means of a pipe 17 with the application end of motor M¹, and hence subjected to the pressure in the application end of motor M¹. The Bourdon tubes 16 each controls two contacts 18—18^a and 18—18^b, and are arranged to operate in succession as the pressure in the application end of motor M¹ increases. For example, for all pressures below ten pounds per square inch, the contact 18—18^a of each of these 35 devices is closed. If the pressure exceeds ten pounds per square inch, however, contact 18—18^a of device K₁¹⁰⁻²⁰ opens, and if the pressure exceeds twenty pounds per square inch, contact 18—18^b of device K₁¹⁰⁻²⁰ closes. In similar manner, the pressure responsive device K₁⁴⁰⁻⁵⁰ is adjusted to open its contact 18—18^a at forty pounds per square inch, and to close its contact 18—18^b at fifty pounds per square inch. Of course, these specific pressures are not essential but are only 45 mentioned for purposes of explanation.

50 The valves E¹ and F¹ are also controlled in part by a contact G¹ which, in turn, is controlled in accordance with the position of piston 5 of motor M¹ in such manner that this contact will 55

be closed at all times except when the piston is moved to its extreme left-hand position in which the braking bars occupy their ineffective or non-braking positions, as shown in the drawing.

The valves D¹, E¹ and F¹ are further controlled by the lever L¹ which, as here shown, is capable of assuming five positions indicated by dotted lines in the drawing. The first position is designated R, and is the position in which the lever is placed when it is desired to restore the braking bars of the car retarder A¹ to their ineffective or non-braking positions. The second position of the lever L¹ is designated N, and is the normal position, that is, the position in which the lever L¹ is placed when no control of the retarder by the lever L¹ is desired. The third and fourth positions of the lever L¹ are designated P¹⁰⁻²⁰ and P⁴⁰⁻⁵⁰, respectively, meaning that when the lever is in position P¹⁰⁻²⁰ a pressure of between ten and twenty pounds per square inch will be maintained in the left-hand, or application end, of motor M¹, and when the lever is in the position P⁴⁰⁻⁵⁰, a pressure of between forty and fifty pounds per square inch will be maintained in the application end of motor M¹. The last position of the lever L¹ is designated P⁸⁰; when the lever is in this position the full available pressure will be admitted to the left-hand end of the motor, it being assumed that the full available pressure is eighty pounds per square inch.

Lever L¹ controls a plurality of contacts 21 to 29, inclusive, adjacent each of which is placed a letter or letters which correspond to the lever position or positions for which the corresponding contact is closed. For example, contact 22 is closed only when lever L¹ occupies its R position. Similarly, contact 24 is closed in the P¹⁰⁻²⁰ position of the lever, the P⁴⁰⁻⁵⁰ position of the lever, or any position intermediate these two positions.

Lever L¹ will usually be located at a point remote from the braking apparatus, as in the control cabin of a classification yard car retarder system, and will be connected with the braking apparatus by means of line wires extending from the control cabin to the braking apparatus.

As shown in the drawing, lever L¹ occupies its normal position, and all circuits leading to the retarder actuating apparatus are therefore open. The valves D¹, E¹ and F¹ are therefore all de-energized, so that the supply of fluid pressure to both ends of cylinder 4 of motor M¹ is cut off, and the right-hand end of cylinder 4 is vented to atmosphere. The contacts 18-18^b of the pressure responsive devices K₁¹⁰⁻²⁰ and K₁⁴⁰⁻⁵⁰ are both open, and the contacts 18-18^a are both closed. Piston 5 of motor M¹ occupies its extreme left-hand position, and the braking bars of the car retarder A¹ therefore occupy their ineffective or non-braking positions. Since piston 5 of motor M¹ occupies its extreme left-hand position, contact G¹ is open.

In explaining the operation of the apparatus as a whole, I will first assume that the operator desires to apply a pressure of between ten and twenty pounds per square inch to the application end of motor M¹ to cause the braking bars of the car retarder A¹ to exert a corresponding pressure on the wheels of a passing car. To do this, he moves lever L¹ to position P¹⁰⁻²⁰, whereupon a circuit for the application valve D¹ becomes closed, which circuit passes from a suitable source of current, here shown as a battery H, through wire 34, contact 24 of lever L¹, wires 35, 36 and

37, contact 28 of lever L¹, line wire 38, contact 18-18^a of pressure responsive device K₁¹⁰⁻²⁰, wire 39, winding 40 of valve D¹, line wire 41, wire 42, contact 21 of lever L¹, and wires 43 and 44 back to battery H. The application valve D¹ therefore becomes energized and admits fluid pressure to the application end of motor M¹ until the pressure reaches ten pounds per square inch, at which time contact 18-18^a of pressure responsive device K₁¹⁰⁻²⁰ opens and interrupts the circuit just traced for valve D¹, so that this valve again becomes deenergized. The applied pressure is, however, retained in the application end of motor M¹. If the pressure in the application end of motor M¹ exceeds twenty pounds per square inch for any reason, contact 18-18^b of pressure responsive device K₁¹⁰⁻²⁰ will become closed and will complete a circuit for the exhaust valve E¹ which passes from battery H through wire 34, contact 24 of lever L¹, wires 35, 36 and 37, contact 28 of lever L¹, line wire 38, contact 18-18^b of pressure responsive device K₁¹⁰⁻²⁰, wire 45, winding 46 of valve E¹, wires 46 and 47, contact G¹, wire 48, line wire 41, wire 42, contact 21 of lever L¹, and wires 43 and 44 back to battery H. The current flowing in this circuit will energize the exhaust valve E¹, and this valve will therefore operate to exhaust fluid from the application end of the motor M¹ until the pressure again decreases to twenty pounds per square inch, whereupon contact 18-18^b will open and winding 40 of the exhaust valve E¹ will again become deenergized.

If, now, the operator desires to increase the pressure in the application end of motor M¹ to between forty and fifty pounds per square inch to increase the braking effect of the car retarder A¹, he moves lever L¹ to its P⁴⁰⁻⁵⁰ position. The application valve D¹ then becomes energized by virtue of a circuit which passes from battery H through wire 34, contact 24 of lever L¹, wires 35, 36, 37 and 49, contact 29 of lever L¹, line wire 50, wire 51, an asymmetric unit J¹ in its low resistance direction, wire 53, contact 18-18^a of pressure responsive device K₁⁴⁰⁻⁵⁰, wires 54 and 39, winding 40 of application valve D¹, line wire 41, wire 42, contact 21 of lever L¹, and wires 43 and 44 back to battery H. The application valve D¹ remains energized under these conditions until the pressure in the application end of motor M¹ reaches forty pounds per square inch, whereupon the circuit just traced for this valve is opened at contact 18-18^a of pressure responsive device K₁⁴⁰⁻⁵⁰. If the pressure in the application end of motor M¹ exceeds fifty pounds per square inch for any reason, exhaust valve E¹ will become energized, and will exhaust fluid from the motor until the pressure again decreases to fifty pounds per square inch, the circuit for the exhaust valve under these conditions being from battery H through wire 34, contact 24 of lever L¹, wires 35, 36, 37 and 49, contact 29 of lever L¹, line wire 50, wire 51, asymmetric unit J¹ in its low resistance direction, wire 53, contact 18-18^b of pressure responsive device K₁⁴⁰⁻⁵⁰, wires 55 and 45, winding 46 of exhaust valve E¹, wires 46 and 47, contact G¹, wire 48, line wire 41, wire 42, contact 21 of lever L¹, and wires 43 and 44 back to battery H.

If the operator desires to admit the full available pressure to the application end of motor M¹, he moves lever L¹ to position P⁸⁰. A circuit for the application valve D¹ is then closed which may be traced from battery H through wires 34 and 56, contact 26 of lever L¹, wires 58 and 42, line

wire 41, winding 10 of valve D¹, wires 39, 54 and 59, an asymmetric unit K¹ in its low resistance direction, wire 61, line wire 50, contact 29 of lever L¹, wires 49, 37, 36 and 35, contact 23 of lever L¹, and wire 44 back to battery H. This circuit does not include any of the contacts of the pressure responsive devices K, and consequently, the full available operating pressure will be admitted to the application end of motor M¹ under these conditions.

It should be pointed out that if the operator moves the lever L¹ from a position corresponding to a higher pressure to a position corresponding to lower pressure, the apparatus will immediately and automatically reduce the pressure in the application end of motor M¹ to a value corresponding to the new position of the lever in a manner which will be apparent from the drawing without tracing the sequence of operation in detail.

In order to restore the braking bars of the car retarder A¹ to their ineffective or non-braking positions, the operator places lever L¹ in its R or restore position. When the lever occupies this position, circuits are completed for both the exhaust valve E¹ and the restoring valve F¹, so that both of these valves now become energized. The circuit for the exhaust valve E¹ passes from battery H through wires 34 and 56, contact 25 of lever L¹, wire 36, contact 27 of lever L¹, line wire 62, an asymmetric unit O¹ in its low resistance direction, wire 45, winding 10 of valve E¹, wires 46 and 47, contact G¹, wire 48, line wire 41, wire 64, contact 22 of lever L¹, and wire 44 back to battery H. The circuit for valve F¹ passes from battery H through wires 34 and 56, contact 25 of lever L¹, wire 36, contact 27 of lever L¹, line wire 62, wire 66, winding 10 of valve F¹, wire 47, contact G¹, wire 48, line wire 41, wire 64, contact 22 of lever L¹, and wire 44 back to battery H. The energization of the exhaust valve E¹ vents to atmosphere the fluid pressure which was previously supplied to the application end of motor M¹, while the energization of the restoring valve F¹ admits fluid pressure to the restoring end of the motor. Piston 5 of motor M¹ therefore now moves to its extreme left-hand position to restore the braking bars to their ineffective or non-braking positions. When piston 5 reaches its extreme left-hand position, contact G¹ opens and interrupts the circuits which were previously closed for valves E¹ and F¹, thus deenergizing these valves. Lever L¹ may then be restored to its normal or N position, and when this is done, all parts will occupy their normal positions in which they are shown in the drawing.

It should be particularly pointed out that with apparatus embodying my invention, I effect the desired control of the magnet valves D¹, E¹, and F¹ by means of only four line wires 41, 62, 38, and 59, a first pair of which 41 and 62 are supplied with current of one polarity from battery H over contacts 22, 25, and 27 of lever L¹ when this lever occupies its R position, a second pair of which 41 and 38 are supplied with current of one polarity from battery H over contacts 21, 24, and 28 of lever L¹ when this lever occupies its P¹⁰⁻²⁰ position, and a third pair of which 41 and 59 are supplied with current of one polarity from battery H over contacts 21, 24, and 29 of lever L¹ when lever L¹ occupies its P⁴⁰⁻⁵⁰ position and with current of the opposite polarity from battery H over contacts 23, 26, and 29 of lever L¹ when this lever occupies its P⁸⁰ position. It should also be pointed out that the desired control of the valves by means of only four line wires is made possible by the use

of the asymmetric units K¹, J¹, and O¹, the particular functions of each of which will now be made clear.

Considering first the asymmetric unit K¹, when lever L¹ occupies its P⁴⁰⁻⁵⁰ position and contact 18-18^a of pressure responsive device K₁⁴⁰⁻⁵⁰ is closed, valve D¹ is energized by current which flows from line wire 50 through wire 51, asymmetric unit J¹ in its low resistance direction, wire 53, contact 18-18^a of pressure responsive device K₁⁴⁰⁻⁵⁰, wires 54 and 39, and winding 10 of valve D¹ to line wire 41, whereas, when lever L¹ occupies its P⁸⁰ position, valve D¹ is then constantly energized by current which flows from line wire 41 through winding 10 of valve D¹, wires 39, 54, and 59, asymmetric unit K¹ in its low resistance direction, and wire 61 to line wire 50. If asymmetric unit K¹ were not provided, then when lever L¹ occupies its P⁴⁰⁻⁵⁰ position and contact 18-18^a of pressure responsive device K₁⁴⁰⁻⁵⁰ opened, the valve D¹ instead of becoming deenergized in the desired manner would remain energized.

Considering next the asymmetric unit J¹, when lever L¹ occupies its P⁸⁰ position, contact 18-18^b of pressure responsive device K₁⁴⁰⁻⁵⁰ is constantly closed, and if the asymmetric unit J¹ were not provided, current would then flow from line wire 41 through wire 48, contact G¹, wires 57 and 46, the winding 10 of valve E¹, wires 45 and 55, contact 18-18^b of pressure responsive device K₁⁴⁰⁻⁵⁰, and wires 53 and 51 to line wire 50, and also from line wire 41 through wire 48, contact G¹, wire 47, the winding 10 of valve F¹, wire 66, asymmetric unit O¹, wire 55, contact 18-18^b of pressure responsive device K₁⁴⁰⁻⁵⁰, and wires 53 and 51 to line wire 50, thus causing valves E¹ and F¹ to become improperly energized. Due, however, to the asymmetric unit J¹, this improper energization of valves E¹ and F¹ is prevented.

Considering next the asymmetric unit O¹, when lever L¹ occupies its R position, current flows from line wire 62 through asymmetric unit O¹, wire 45, winding 10 of valve E¹, wires 46 and 47, contact G¹, and wire 48 to line wire 41, and also from line wire 62 through wire 66, winding 10 of valve F¹, wire 47, contact G¹, and wire 48 to line wire 41. If the asymmetric unit O¹ were not provided, then when lever L¹ occupies its P⁴⁰⁻⁵⁰ position and the pressure in the motor cylinder increased to 50 pounds per square inch, current would flow from line wire 50 through asymmetric unit J¹, wire 53, contact 18-18^b of pressure responsive device K₁⁴⁰⁻⁵⁰, wires 55 and 66, the winding 10 of valve F¹, wire 47, contact G¹, and wire 48 to line wire 51, thus causing the valve F¹ to become improperly energized under these conditions.

Although I have herein shown and described only one form of apparatus for the control of railway car retarders embodying my invention, it is understood that various changes and modifications may be made therein within the scope of the appended claims without departing from the spirit and scope of my invention.

Having thus described my invention, what I claim is:

1. Apparatus for controlling the supply of fluid pressure to a car retarder actuating motor comprising an application magnet, an exhaust magnet, a normally closed contact responsive to the pressure in the application end of said motor and arranged to open at a predetermined pressure, a normally open contact responsive to the pressure in the application end of said motor and arranged to become closed at a pressure somewhat higher

than said predetermined pressure, two line wires, means for reversibly supplying current to said line wires, two asymmetric units, means including one of said asymmetric units for connecting said application magnet with said two line wires, means including said normally closed contact and the remaining asymmetric unit for connecting said application magnet with said line wires, said two asymmetric units being oppositely disposed with respect to said line wires, and means including said remaining asymmetric unit and said normally open contact for connecting said exhaust magnet with said two line wires.

2. Apparatus for controlling the supply of fluid pressure to a car retarder actuating motor comprising an application magnet, an exhaust magnet, a normally closed contact responsive to the pressure in the application end of said motor and arranged to open at a predetermined pressure, a normally open contact responsive to the pressure in the application end of said motor and arranged to become closed at a pressure somewhat higher than said predetermined pressure, two line wires, means for reversibly supplying current to said line wires, two asymmetric units, means including one of said asymmetric units for connecting said application magnet with said two line wires, means including said normally closed contact and the remaining asymmetric unit for connecting said application magnet with said line wires, said two asymmetric units being oppositely disposed with respect to said line wires, a third contact controlled by said motor, and means including said third contact, said normally open contact and said remaining asymmetric unit for connecting said exhaust magnet with said line wires.

3. Apparatus for controlling the supply of fluid pressure to a car retarder actuating motor comprising an application magnet, a restoring magnet, an exhaust magnet, means for at times energizing said application magnet; a first, a second, and a third line wire; means for supplying current to said first and second and said first and third line wires, means for connecting said restoring magnet with said first and second line wires, two asymmetric units, means including one of said asymmetric units for connecting said exhaust magnet with said first and second line wires, a contact responsive to the pressure in the application end of said motor and arranged to operate at a predetermined pressure, and means including said contact and the remaining asymmetric unit for connecting said exhaust magnet with said first and third line wires.

4. Apparatus for controlling the supply of fluid pressure to a car retarder actuating motor comprising an application magnet, an exhaust magnet, a restoring magnet; a first, a second, and a third line wire, means for supplying current of one polarity to said first and second line wires and of one polarity or the other to said first and third line wires, means for connecting said restoring magnet with said first and second line wires, three asymmetric units, means including a first one of said asymmetric units for connecting said exhaust magnet with said first and second line wires, a normally closed contact responsive to the pressure in the application end of said motor and arranged to open at a predetermined pressure, a normally open contact responsive to the pressure in the application end of said motor and arranged to become closed at a pressure which is somewhat higher than said predetermined pressure, means including a second one of said asymmetric units for connect-

ing said application magnet with said first and third line wires, means including a third one of said asymmetric units and said normally closed contact for connecting said application magnet with said first and third line wires, and means including said third asymmetric unit and said normally open contact for connecting said exhaust magnet with said first and third line wires.

5. Apparatus for controlling the supply of fluid pressure to a car retarder actuating motor comprising an application magnet, an exhaust magnet, a restoring magnet; a first, a second, and a third line wire, means for supplying current of one polarity to said first and second line wires and of one polarity or the other to said first and third line wires, a first contact responsive to the position of the piston of said motor, means including said first contact for connecting said restoring magnet with said first and second line wires, three asymmetric units, means including a first one of said asymmetric units and said first contact for connecting said exhaust magnet with said first and second line wires, a normally closed contact responsive to the pressure in the application end of said motor and arranged to open at a predetermined pressure, a normally open contact responsive to the pressure in the application end of said motor and arranged to become closed at a pressure which is somewhat higher than said predetermined pressure, means including a second one of said asymmetric units for connecting said application magnet with said first and third line wires, means including a third one of said asymmetric units and said normally closed contact for connecting said application magnet with said first and third line wires, and means including said third asymmetric unit and said normally open contact as well as said first contact for connecting said exhaust magnet with said first and third line wires.

6. Apparatus for controlling the supply of fluid pressure to a fluid pressure motor comprising a single source of electromotive force; first, second, third, and fourth line wires; means for at times supplying current of one polarity from said source to said first and second line wires and at other times to said first and third line wires, means for at still other times supplying current of one polarity or the other from said source to said first and fourth line wires, an application magnet, an exhaust magnet, a restoring magnet, first and second normally closed contacts responsive to the pressure in the application end of said motor and arranged to open at progressively increasing pressure values, first and second normally open contacts responsive to the pressure in the application end of said motor and arranged to become closed at pressure values which are somewhat higher respectively than the pressure values at which said first and second contacts open, a fifth contact responsive to the position of the piston of said motor, three asymmetric units, means including a first one of said asymmetric units for connecting said application magnet with said first and fourth line wires, means including a second one of said asymmetric units and said second normally closed contact for connecting said application magnet with said first and fourth line wires, means including said first normally closed contact for connecting said application magnet with said first and third line wires; means including said second asymmetric unit and said second normally open contact as well as said fifth

contact for connecting said exhaust magnet with said first and fourth line wires, means including said first normally open contact and said fifth contact for connecting said exhaust magnet with said first and third line wires, means including the third one of said asymmetric units and said

fifth contact for connecting said exhaust magnet with said first and second line wires, and means including said fifth contact for connecting said restoring magnet with said first and second line wires.

JOHN W. LIVINGSTON.
